DESIGN FOR A FLUORESCENT LAMP

Earl F. Miller, Creve Coeur, Ill.

Application January 16, 1942, Serial No. 105,247

Term of patent 14 years

To all whom it may concern:

Be it known that I, Earl F. Miller, a citizen of the United States, residing at Creve Coeur, in the county of Tazewell and State of Illinois, have invented a new, original, and ornamental Design for a Fluorescent Lamp, of which the following is a specification, reference being had to the accompanying drawing, forming part thereof.

Figure 1 is a top plan view of the fluorescent lamp embodying my new design.

Figure 2 is a bottom plan view thereof, and

Figure 3 is a side elevational view thereof.

The essential feature of my design for a fluorescent lamp resides in the concentric arrangement of two annular fluorescent tubes interconnected by the specific assembling and mounting fixture as shown.

I claim:

The ornamental design for a fluorescent lamp, as shown and described.

EARL F. MILLER.
